CAN COVER CLINCHER

Merton L. Dodge, Seattle, Wash.

Application August 19, 1947, Serial No. 769,385

2 Claims. (Cl. 81—15)

1

This invention relates to can cover clinching tools and it has reference more particularly to a hand operated cover clinching tool, designed especially for use in home canning operations and manually operable to loosely secure the covers in place on the cans, thus to retain the contents in the can while being heated or exhausted prior to the final double seaming operation and processing, and to facilitate handling of the cans.

For a better understanding of the present invention, it will be explained that tin cans are now quite extensively used for home canning operations and that such cans are sealed by the double seaming of the ends or covers to the can bodies. Since the products that are canned are most generally heated to approximately boiling point (212° F.) prior to the double seaming of the end or cover to the can body, it is quite advantageous and is practical, as is well understood in the art, that the covers be placed on the cans and loosely clinched thereto to retain the contents in the cans during the exhausting operation, but permitting steam and air escape-
ment.

Many home canners have small hand operated double seamers and sometimes use the double seamer itself as the means for loosely clinching the cover flange over the can body flange, but this operation is rather slow and impractical for various reasons. Spot clinching that is done by means of tools or machines not especially designed for this purpose, usually deforms the cover flange so that effective double seaming is not insured.

In view of the above and for various other reasons, it has been the principal object of this invention to provide a hand-operated can cover clincher of pliers type, and of such design that a short portion of the can cover flange may be curled thereby beneath the body flange to an exact amount, thus, at that point, to secure the cover loosely in place. Furthermore, it is essential to do this without causing any abrupt dent, irregularity or any undesirable deformation that will cause difficulty in double seaming, or in any way impair the integrity of the sealed connection.

More specifically stated, the object of the present invention is to provide a hand operated can cover clincher, comprising a tool of pliers type having one jaw equipped with a chuck for engaging against the counter-sink wall of the can cover and the other jaw being equipped with a die opposingly related to the chuck to engage the

2

lip or outer edge of the can cover flange, and formed with a groove designed to receive the lip portion therein and whereby, upon the clamping of the jaws together, the engaged part of the flange will be curled beneath the can body flange; the chuck and die being so related to each other on the jaws that the clinching will be limited to an exact and predetermined amount.

Other objects of the invention reside in the details of construction of parts embodied in the tool, in their relationship and in the mode of use of the tool, as will hereinafter be fully described.

In accomplishing the above mentioned and other objects of the invention, I have provided the improved details of construction, the preferred forms of which are illustrated in the accompanying drawings, wherein—

Fig. 1 is a top view of a can with cover applied thereto and showing a cover clinching tool, embodied by the present invention, as applied to the cover in a flange clinching operation.

Fig. 2 is an enlarged, sectional detail of portions of the can body and cover as assembled prior to clinching, and indicating the application of the chuck and clincher die of the present tool thereto

Fig. 3 is a similar view, showing the cover flange as being clinched beneath the can body flange by the closing together of the jaw portions of the tool.

Fig. 4 is a sectional detail showing a completed clinch and illustrating the engagement of the inwardly curled edge of the cover flange with the body flange to limit the extent to which the cover may lift from the can.

Fig. 5 is an underside view of the jaw portions of the present clinching tool, showing the relationship and shape of the coating portions of the chuck and clincher die, as applied to the jaws of the tool.

Referring more in detail to the drawings—

In Figs. 2, 3 and 4, 10 designates the cylindrical body wall of a typical tin can, and 12 designates the out-turned peripheral flange at the upper end of the can body over which the end or cover is applied and to which its flange is joined in the double seam to seal the can. The can cover is designated by numeral 13 and this is shown as being formed with a counter-sink having a cylindrical wall portion 14 that fits closely within the upper end of the cylindrical can body and from which counter-sink wall a flange 15 extends horizontally and outwardly to overlie the body flange 12. Before clinching and

before double seaming, the flange 15 extends substantially beyond the periphery of the body flange, as shown in Fig. 2, and has a peripheral, downwardly and slightly inwardly curled lip 17.

The purpose of the present tool is to curl a short segment of the lip portion 17 of the cover flange beneath the body flange 12 so that the cover cannot, at that point, be lifted out of the can body, but at the same time will provide for a certain amount of lift that will allow steam and air to escape from the can during the preliminary processing of the can's contents prior to double seaming.

In its present preferred form of construction, the clinching tool is made in pliers form as seen in Fig. 1 in that it comprises two crossed hand levers 20 and 21, formed with circular and rather extended bearing portions, as at 22 in Figs. 1 and 5, that are engaged concentrically and flatly together, and are pivotally joined at their centers by a stud or rivet 24. The levers extend, at one side of the pivot, as handle portions 20' and 21' and at the other side of the pivot terminate in flat jaw portions 25 and 26, which lie in the same plane and are formed with straight adjacent edges 27 and 28 that may be closed flatly together, thus to limit the extent of closing and incidentally to definitely limit the extent of the inward curling of the cover flange segment in a clinching operation, as will presently be explained.

Secured to the underside of the jaw portion 25 of the tool is a hard metal forming block 30, which I designate as the "chuck" and likewise secured to the underside of the opposite jaw 26 is a forming block 31 which I designate the "die." These two blocks, 30 and 31, are disposed directly opposite each other and are adapted, when the jaws are opened apart, to be applied to the cover to receive a portion of its flange 15 between them for a clinching operation as has been illustrated in Figs. 1 and 2.

It is an important detail that the chuck 30 is formed at that side which faces the block 31, with a radially curved or arcuate side surface 32, shown best in Fig. 5. When the tool is applied to the can cover, the bottom surface of the chuck engages against the cover, as in Fig. 3, and the curved surface 32 will engage against the counter-sink wall 14. The radius of curvature of the chuck surface 32 is made equal to or slightly less than the radius of curvature of the counter-sink wall of cans of smaller size, so that the tool can be used with cans of a range of sizes.

The lower edge or corner of the chuck 31 should be so curved that it will fit snugly in the bend where the counter-sink wall 14 joins with the body portion of the cover.

That side surface of the die 31 that is directly opposed to the curved side surface 32 of the chuck is straight; this surface being designated at 34 and is best shown in Fig. 5. When the jaws 25-26 are opened apart and the device applied to a can cover for a flanging operation, the straight side 34 of the die should engage tangentially with the lip of the cover midway of its ends, and the tool will assume a relationship to the can substantially as seen in Fig. 1.

The straight side surface 34 of the die is formed, from end to end, at a proper level to receive the lip edge of the cover flange, with a longitudinal groove 40, as shown in Figs. 1, 2 and 3. This groove is so located as to receive the downwardly curled lip portion 17 of the cover

flange therein when the jaws are clamped against the cover for a clinching operation and is so shaped that with the closing together of the jaws of the tool, the engaged segment of the cover will be curled inwardly and upwardly so that it assumes a final position substantially as illustrated in Figs. 3 or 4. The clinch is so formed that the cover will be permitted to lift slightly, for example, as from the position in Fig. 3 to the position of Fig. 4, for the escape of steam and air from the can during a pre-heating operation.

The extent to which a clinch is formed is definitely limited by the closing together of the adjacent edge surfaces 27-28 of the jaws 25 and 26; it being understood that the chuck 30 and die 31 are so located on these jaws that when the edge portions of the jaws are brought flatly together, the clinch would be completed to the desired, exact amount.

Another important feature of this invention resides in the fact that the straight edge 34 of the die 31 is of such length that it will extend to the full length of the chord that defines the segment of the flange that is curled by the clinching tool. Therefore no dent, shoulder or bend will be formed by or at the ends of the die that would cause a roll of the double seamer to bump or jump in the double seaming operation. The outer surface of the clinch will be perfectly straight, as seen at 45 in Fig. 1.

With the can cover seated in the end of the can body as seen in Fig. 2, the manner of using the tool is merely to open the jaws of the clincher tool apart and apply the chuck and die portions 30 and 31 to the selected portion of the cover flange, as in Fig. 2 and then clamp them together. In this clamping operation, the chuck seats against the counter-sink wall 14 and the periphery of the cover flange will be received in the die groove 40. With the closing together of the jaws, the engaged segment of the flange will be inwardly and upwardly curled to the form shown in Fig. 3, and is stopped by the closing together of the jaws, as in Fig. 1. The cover may be lifted out of its seat to the position shown in Fig. 4, by the expanding air or steam in the can during heating. Clinches so formed at three equally spaced locations about the periphery of a can cover are sufficient to hold the cover in place but may be made at more or less places as desired.

Such tools may be made in various designs other than that illustrated, and may be of various materials and in various sizes without departing from the spirit of the invention.

The gist of the invention resides in the details of the chuck and die and in the securing of these parts to the jaws in such relationship to each other and to the edges of the jaws that a clinch of a definite amount will be formed with the closing of the jaws together.

Having thus described my invention, what I claim as new therein, and desire to secure by Letters Patent is:

1. A tool of the character described comprising a pair of pivotally connected levers providing handle portions and jaw portions, said jaw portions having forming blocks projecting from corresponding side faces thereof; said blocks having opposingly related work engaging faces extending in the general longitudinal direction of the tool; one of the work engaging faces being straight and having a groove therein extending in the longitudinal direction of the tool, and the other

of said work engaging faces being arcuate and extending in the general direction of the tool, and curved between its ends toward the straight face.

2. A tool of the character described comprising a pair of levers pivotally connected intermediate their ends to form jaw portions and handle portions; said jaw portions having opposing flat faces and forming blocks projecting from corresponding sides of the jaws; said blocks having opposing work engaging faces which extend in a general longitudinal direction of the tool and spaced from each other when the jaws are closed, one of the work engaging faces being straight and having a groove therein extending in the longitudinal direction of the tool and the other work

engaging face being arcuate and extending in the longitudinal direction of the tool.
